(57) **CLAIM**

We claim the ornamental design for a faceplate for a videogame controller, as shown and described.

DESCRIPTION

FIG. 1 is a front perspective view of an ornamental design for a faceplate for a videogame controller; FIG. 2 is a front elevational view thereof;

FIG. 3 is a back elevational view thereof;

FIG. 4 is a right side elevational view thereof;

FIG. 5 is a left side elevational view thereof;

FIG. 6 is a top view thereof;

FIG. 7 is a bottom view thereof; and,

FIG. 8 is a front perspective view showing the faceplate for a video game controller coupled to a video game controller. The broken lines illustrate unclaimed portions of the faceplate and form no part of the claimed design. The broken lines in FIG. 8 illustrate environment and forms no part of the claimed design.
